UNITED STATES PATENT OFFICE.

WILLIAM F. HENDRY, OF OSSINING, NEW YORK, ASSIGNOR, BY MESNE ASSIGNMENTS, TO NATIONAL CARBON COMPANY, INC., OF NEW YORK, N. Y., A CORPORATION OF NEW YORK.

DRY-CELL SEALING DEVICE.

Application filed January 21, 1925. Serial No. 3,831.

This invention relates to new and useful improvements in dry cell sealing devices.

The object of the invention is to provide a mechanically operating device for applying a seal of pitch or the like to the tops of dry cells and do away with the customary method of pouring the pitch with a ladle.

With this object in view I provide a container from which an annular layer of pitch or other suitable sealing material may flow on top of the dry cell under the control of a valve operated in a predetermined manner. Means are provided for properly centering the cell during the pouring operation and for protecting the central carbon electrode. In order to prevent the collapsing of the column of pitch that is being deposited on the cell after the closure of said valve, the arrangement is so provided that at this time a blast of air is sent through the column.

These and other features of the invention will more clearly appear from the following detailed description of an embodiment thereof and the appended claims.

The drawings illustrate as much of a sealing device as is necessary for an understanding of the invention, parts of the device being shown in side elevation and others in vertical cross-section. Obviously, the details of the construction may be varied, the present disclosure being intended mainly to illustrate the functions to be performed in accordance with the present invention.

A dry cell 1 to be sealed with pitch is placed on a platform 2 below the pitch supply nozzle 3. The cell consists of a zinc container electrode 4 and a carbon electrode 5 centrally located within a mass or bobbin of depolarizing material 6.

The purpose of the operations to be hereinafter described is to fill the annular free space between the tops of electrodes 4 and 5 with a seal of pitch. First the operator removes his foot from a lever 7 and pulls down a second lever 8. The lever 7 is pivoted at 9 to a leg 10 of a table 11 on which the platform 2 is supported. By means of a spring 12 stretched between the lever 7 and table 11, the lever is rotated in a clockwise direction. In response to this movement, the platform 2 with cell 1 are caused to rise, the platform being carried on the free end of a rod 13 which projects through table 11 and is pivoted to lever 7 at 14.

In its downward movement the lever 8, 55 which is pivoted at 15 to an upright 16, causes a plunger 17 to descend towards cell 1. One end of plunger 17 is rotatably supported on lever 8 at 18, and the other end is shaped into a bell-shaped cap 19 adapted to receive the top 60 of carbon electrode 5. Owing to the shape of cap 19 it will center cell 1 on the platform 2 even in case the cell were improperly aligned. Slightly above cap 19 the plunger 17 is formed into a valve 20 adapted to close the 65 nozzle 3. When the plunger descends, the valve 20 is opened and pitch is permitted to flow from a reservoir 21 between the tops of electrodes 4 and 5, the end of carbon 5 being protected by means of cap 19 against which it 70 is firmly held by spring 12. The pitch in reservoir 21 is maintained in a viscous condition by any suitable heating means, such as a jacket 22 through which steam is passed. The lower part of plunger 17 passes through 75 the reservoir 21 and the escaping of pitch is guarded against by means of a packing 23.

When the annular space in cell 1 has been filled with pitch nearly to the top of container 4, the operator pushes up the lever 8 and 80 presses down the lever 7, restoring thus the cell 1 to its normal position and closing the valve 20. While the closure of the valve cuts off the flow of pitch from reservoir 21, a column of pitch suspended in air will drop down 85 on top of the dry cell. This column would normally collapse over the protruding end of the carbon electrode, and in order to prevent this, a blast of air is sent through the column. The air is sent through a conduit 90 24 and a passageway 25a traversing the lower half of plunger 17 under the control of a valve 25 which is operated in the following manner:

Normally, the valve 25 is closed, being held 95 against its seat 26 by means of a coiled spring 27. During the downward movement of lever 8 the valve 25 remains closed. However, during the upward movement of lever 8, just before valve 20 closes (the position illustrated in the drawing), a cam 28 engages a finger 29 projecting from stem 30 of valve 25 and lifts the latter against the tension of spring 27. The cam 28 is carried on the end of a rod 31 which is mounted on lever 100 8 by means of straps 32 permitting the rod 31 to move horizontally. The end of rod 31 is provided with a longitudinal slot 33

through which the pin 15 passes. A coiled spring 34 surrounding rod 31 between one of the straps 32 and cam 28 presses the latter towards the finger 29. Inasmuch as the cam 28 is carried by the lever 8 it will be moved with the latter and into engagement with finger 29. During the continued upward movement of lever 8, the finger 29 will force the cam 28 and rod 31 to the right against the tension of spring 34 until the center of the cam is passed, whereupon the valve 25 is closed by spring 27 and the cam 28 is forced by spring 34 to ride on top of finger 29.

15 It will be seen, therefore, that during the upward movement of lever 8 the valve 25 is opened slightly before the closure of valve 20 and not closed until shortly after the closure of said valve 20. During the following 20 downward movement of lever 8, the cam 28 rises over finger 29 without, however, opening the valve 25.

What I claim is:

1. In a dry cell sealing device, a container 25 for sealing material, means for controlling the flow of material from said container in the form of a hollow cylinder, and means for blowing air through said mass from the inside of the cylinder in a direction at right angles to the walls thereof.

2. In a dry cell sealing device, a container 30 for sealing material, an annular valve in said container, means for operating said valve to permit the flow of a cylindrical mass of material from said container, means including an air valve for controlling the flow of air 35 through said cylindrical mass, and operating means for said air valve responsive to the actuating of said first-mentioned valve.

40 3. In a dry cell sealing device, a container for sealing material having a nozzle, a valve in said nozzle, a bell-shaped projection adapted to receive a carbon electrode depending from said valve, a plunger carrying said valve, a pivoted lever for actuating said plunger, a platform for the dry cell below said nozzle and valve, and a lever normally tending to move said platform toward said nozzle, said valve being opened by a movement thereof toward said platform.

45 4. In a dry cell sealing device, a container for sealing material having a nozzle, a valve in said nozzle, a bell-shaped projection adapted to receive a carbon electrode depending from said valve, a plunger carrying said valve, a pivoted lever for actuating said plunger, a platform for the dry cell below said nozzle and valve, a lever normally tending to move said platform toward said nozzle, means including an air valve for controlling the flow of 50 air through said projection, and means for

opening said air valve responsive to closing of said first mentioned valve.

5. In a dry cell sealing device, a container 55 for sealing material having a nozzle, a valve in said nozzle, a bell-shaped projection adapted to receive the end of a carbon electrode depending from said valve, a plunger carrying said valve, a pivoted lever for actuating said plunger, a platform for the dry cell below 60 said nozzle and valve, a lever normally tending to move said platform towards said nozzle, means including a normally closed air valve controlling the passage of air through said projection, and a cam cooperating with 65 said air valve to open it during only a part of a movement of said pivoted lever.

6. In a dry cell sealing device, a container 70 for sealing material having a nozzle, a valve in said nozzle, a bell-shaped projection adapted to receive the carbon electrode depending from said valve, a plunger projecting through 75 said container and carrying at its lower end said valve, a pivoted lever with which the upper end of said plunger is connected, a platform for the dry cell below said nozzle and valve, a rod carrying said platform, a spring normally tending to move said rod upwards, a lever for moving said rod downwards, a normally closed spring-pressed valve, a passageway for air controlled by 80 said spring-pressed valve, a rod for opening said valve against spring tension, and a cam mounted on said pivoted lever for actuating said rod during a part of the upward movement of said lever.

7. In a dry cell sealing device a container 85 for sealing material, means for controlling the flow of material from said container in a cylindrical mass for a certain length of time, and means for conducting a blast of air to the center of said mass and for guiding said blast in a direction at an angle to the wall of the container, said conducting means being operated by the first mentioned means at a predetermined point in its movement.

8. The method of sealing the top of a filled cylindrical container with a viscous fluid which comprises flowing a quantity of said material into said container in the form of an annular stream, cutting off said flow when the desired quantity has been discharged into the container, conducting an annular blast of air to the open end of said container and toward the sides thereof to prevent any excess of said material from being undesirably deposited in the central area of the filled container.

In testimony whereof, I have signed my name to this specification this 13th day of January, 1925.

WILLIAM F. HENDRY.
